CONTROL SYSTEM FOR ELEVATORS

Filed May 27, 1929

FIG. 1.

FIG. 2.

UNITED STATES PATENT OFFICE

HAROLD W. WILLIAMS, OF WILKINSBURG, PENNSYLVANIA, ASSIGNOR TO WESTINGHOUSE ELECTRIC & MANUFACTURING COMPANY, A CORPORATION OF PENNSYLVANIA

CONTROL SYSTEM FOR ELEVATORS

Application filed May 27, 1929. Serial No. 366,278.

My invention relates to control systems for motors and has particular relation to systems of control for hoists and elevators.

Another object of my invention is to provide a system for elevators operating at working speed within a "local" zone of operation and at an increased speed in another or "express" zone of operation, wherein temporary exit and re-entry of the car from and to the local zone will insure the operation of the car at the working speed.

Another object of my invention is to provide a control system for elevators adapted to operate at express and local speeds in order that the predetermined operation shall be effected even under slightly abnormal conditions.

My invention is particularly applicable to control systems for elevators adapted to operate in local and in express zones and in which the operator may so control the system as to defeat the desired object and comprises an additional inductor plate properly located in a hatchway in order to ensure the change from express speed to local speed.

My invention will be described in combination with the accompanying drawings wherein:

Figure 1 is a diagrammatic view of a bank of elevators serving a plurality of floors, 14 in number, and showing the relative positioning of the express and local zones; and

Fig. 2 is a diagrammatic view of the control system for an elevator embodying my invention, as applied to a simplified form of speed-control system.

In Fig. 1 are shown three elevator hatchways, indicated as A, B and C, in which elevator cars indicated as A', B' and C', respectively, operate in the usual manner. The cars are respectively suspended by means of cables extending from them over hoisting drums A'', B'' and C'', respectively, to counterweights A''', B''', and C'''.
A pair of inductor irons are normally positioned in each of the hatchways, these inductor irons defining the point between the local and the express zones. For example, in the hatchway A, inductor iron 15 is indicated as positioned slightly above the second-floor

level and on the left-hand side of the hatchway. A similar inductor iron 16 is shown as located slightly below the fourth-floor level upon the right-hand side of the shaft. With this arrangement, we may assume that the elevator A is to operate to give express service; that is, to stop at none of the floors between the first and fourth floors and thereafter to proceed as a local elevator from the fourth to the fourteenth floor; that is, the car will make all necessary stops between the fourth and the fourteenth floors in response to the usual passenger-operated signal devices ordinarily provided in elevator-control systems. By a similar arrangement of inductor irons 17 and 18 in the hatchway B, the elevator therein may be operated as an express elevator to the ninth floor and as a local elevator for the remaining floors, while the car in the hatchway C may give local service to the first eight floors and express service from the ninth floor to the upper terminal.

This express and local operation is usual in very tall buildings in order to prevent the traffic to or from a given section of the building from crowding the traffic to or from a different section of the building. As may readily be seen, should the elevator A', for example, start from the first floor and make all of the stops at floors between the first and fourteenth, the capacity of the elevator would have to be very great in order to provide room on the car to take on the passengers at the twelfth or thirteenth floors. Similarly, on a "down" trip, the condition of stopping at all of the floors would cause the car to be so crowded, as it approached the few lower floors, that there would be no room for additional passengers from these floors to be cared for by this car. This local and express system of operating elevators is quite usual in present day buildings of more than ten stories in height.

A system of this kind is disclosed and claimed in application, Serial No. 197,830, filed June 10, 1927, by F. E. Lewis and assigned to the Westinghouse Electric & Manufacturing Company, now Patent No. 1,793,497, Feb. 24, 1931.

Fig. 2 illustrates a diagram of connections

of a control system with which the particular device embodying my invention is employed. An elevator car C is suspended by means of a cable CA which passes over a hoisting drum D to a suitable counterweight CW. The hoisting drum D may be driven in any suitable manner and, in the illustrated embodiment, the driving means comprises a motor-generator-motor set of the Ward-Leonard type. This set comprises a driving motor M provided with a shunt field winding MF and having its armature M' directly coupled to the armature G' of a generator G. The generator G is of the compound-wound type and comprises an armature G', a series field winding GSF, a separately excited field winding GF and a demagnetizing field winding GAF. The armature G' of the generator G is connected in "loop circuit" with the armature EM' of an elevator-hoisting motor EM. The elevator motor EM is provided with a separately excited field winding EMF and has its armature EM' directly coupled to the hoisting drum. The direction and speed of the hoisting motor EM is controlled in any suitable manner, as by controlling the direction and amount of current through the field winding GF of the generator G.

The control elements include an "up"-direction switch 1, and a "down"-direction switch 2 which are effective, when properly energized, to selectively connect the generator field winding GF to line conductors L1 and L2, with the current passing therethrough in opposite directions. The speed of the motor EM is varied by the inclusion or exclusion of a resistor R selectively controlled by a speed relay 3. Various direction and speed relays may be controlled from the elevator car C by means of a car switch CS, for example, a plurality of slow-down and stop inductor relays 6, 7, 8, 9 and 11, and a pair of electromagnetic relays 4 and 5. The connections between the various relays and switches will be hereinafter described in connection with an assumed operation of the elevator.

Let it be assumed that it is desired to move a car, for example, the car A' upwardly. The operator moves the handle of the car switch CS to the right to energize the "up"-direction switch 1 by way of a circuit which extends from line conductor L1, through conductors 22 and 23, contact 24, sector 25 of car switch CS, contact member 26, conductor 27, the coil of "up"-direction switch 1 and the conductor 28, to line conductor L2. "Up"-direction switch 1, when actuated, energizes the field winding GF with current in one direction by way of a circuit extending from line conductor L1, through conductors 29 and 31, contact members b on "up"-direction switch 1, conductor 32, field winding GF, conductors 33 and 34, contact members c on

"up"-direction switch 1, conductor 36, resistors R and R' and conductor 38, to line conductor L2. This energization of the generator field winding GF causes the generator G to supply the hoisting motor EM with voltage in one direction and the car starts upwardly. 70

The "up"-direction switch 1 also completes a self-holding circuit which extends from line conductor L1, through conductors 22 and 42, the normally closed contact members controlled by inductor relay 7, conductors 41 and 39, contact members a on "up"-direction switch 1, the coil of "up"-direction switch 1 and conductor 28, to line conductor L2. The elevator car, thus started, continues to operate at a predetermined and relatively slow speed. 75

If the operator desires to cause the car to move upwardly at a higher speed, he moves the handle of the car switch CS farther to the right to effect engagement of the contact sector 25 with the fixed contact member 43. This operation establishes a circuit for energizing the speed relay 3 which may be traced as follows:—from line conductor L1, through conductors 22 and 23, contact members 24, 25 and 43 on car switch CS, conductors 44 and 46, the coil of speed relay 3 and conductor 47, to line conductor L2. The actuation of speed relay 3 closes its contact members a to shunt the resistor R from the circuit of the generator field winding GF by way of conductors 49, 52 and 51, with the result that the motor operates at a higher speed. 90 This speed, which is hereinafter referred to as the "high speed", is intended to be the highest speed which the elevator will attain while in a local zone. 100

The speed relay 3 completes a self-holding circuit which extends from line conductor L1, through conductors 22 and 56, the contact members of down-slow-down-inductor relay 8, conductor 54, the contact members of "up"-slow-down inductor relay 6, conductor 53, contact members b on speed relay 3, conductor 46, the coil of speed relay 3 and conductor 47, to line conductor L2. 105

It is, therefore, seen that the motor will be maintained in operation at its high speed until the slow-down inductor relay 6 has been operated by coming into cooperative relation with a slow-down inductor plate SU, (Fig. 2) one of which is mounted adjacent to each of the floors at which the elevator is to stop. An inductor plate SD for each floor, suitably disposed with respect thereto, is also provided for entering into cooperative relation with down slow-down inductor relay 8 and effecting the operation thereof to initiate the stopping of the car at a selected floor when the car is descending. An inductor plate S for each floor is provided for entering into cooperative relation with stop-inductor relay 7 to effect the final stop- 115 120 125 130

ping of the elevator car. The coils of the inductor relays 6, 7 and 8 are energized to render the relays operable only when the car switch has been returned to normal position, 5 because the circuits for these coils include a contact 60 on the car switch CS that is closed only when the car switch is in "off" position.

In series with the generator field winding GF and, therefore, in series-circuit relation 10 to resistor R, is connected a second resistor R' which may be excluded from this circuit by the operation of the relay 5. The function of this resistor R' is to maintain the speed of the motor at the high-speed condition herein- 15 before mentioned, and it is desired to exclude this resistor when the car passes into the high-speed zone, thereupon causing the motor to operate at express speed or at a speed above the usual high speed. If the 20 high speed of the elevator be 600 feet per minute, the express speed may be considerably in excess of that speed, for example, 750 to 900 feet per minute, but it is to be understood that these values are illustrative 25 and that the express speed may be any value within the well known safety limits.

The relay 5 is energized through the agency of a pair of inductor relays 9 and 11 in combination with a relay 4, certain 30 contact members of the relay 4 being electrically connected in series with the coil of relay 5. The operation of relays 9, 11, 4 and 5 may be best described with reference to an assumed cycle of operation. Assume the 35 conditions of operation described for the elevator car A' with reference to Fig. 1, the elevator may be started from the first floor by a movement of the car switch CS and the consequent operation of the control system 40 previously described, and the car will move upwardly on its first trip at high working speed. When the car arrives at the fourteenth floor and is reversed for the "down" trip, the movement of the car switch CS, 45 to the left, closes a circuit for the coil of inductor relay 11 which may be traced as follows:—from line conductor L1, through conductors 22 and 61, the coil of relay 11, conductor 82, one set of contacts of a double- 50 pole switch 12 mounted in the car C, conductor 83, contact members e on down-direction switch 2 and conductors 65, 66 and 28, to line conductor L2. Until the inductor relay 11 passes the "down" inductor iron 16 55 (in this case slightly below the fourth floor level) this relay is ineffective to control any operation of the motor. The car will, therefore, proceed as a local elevator, that is, at speeds not greater than high speed, from the 60 fourteenth to the fourth floors, making the necessary stops in response to passenger-operated signals. As the car leaves the fourth floor, the relay 11 passes the inductor iron 16, and the relay is actuated to close its 65 contact members, thus completing a circuit

to actuate relay 4 which extends from line conductor L1, through conductors 22, 61 and 59, the contact members of relay 11, conductor 58a, the contact members of relay 9, conductor 58, the coil of relay 4 and a part 70 of conductor 47, to line conductor L2. The relay 4 closes its contact members a, thereby energizing the coil of relay 5 through a circuit which may be traced as follows:

From line conductor L1, through conductor 71, the coil of relay 5, conductor 63, contact members a on relay 4 and conductor 72, to line conductor L2. Relay 5, when energized, closes its contact members and shunts or short-circuits resistor R' through the 75 conductors 51, 52 and 73. Exclusion of resistor R' from the circuit of the generator field winding GF increases the car speed to the abnormal or express speed, and the car will travel at this express speed to the first 80 floor. Suitable limit switches are provided to cause the car to stop at the first floor, and these limit switches are generally operated, in elevator systems, to stop the car at its 85 limits of travel. It is not thought necessary 90 to illustrate them here.

The relay 4, when actuated, closes a self-holding circuit extending from line conductor L1, through conductor 71 and 57, contact members c on relay 4, conductors 74 and 58a, the contact members of an inductor relay 9, conductor 58, the coil of relay 4 and a part of conductor 47, to line conductor L2. 95

When the car is again started upwardly, the relay 4 remains energized, since the only 100 point at which the circuit for this relay may be broken is at the normally closed contact members of relay 9 and, therefore, the car accelerates to and moves at express speed until it arrives at the third floor. As the car passes 105 the second floor, the inductor iron 15, co-operating with the relay 9, causes this relay to open its contact members and to de-energize the relay 4 and, consequently, the 110 relay 5.

The coil of relay 9 is energized at all 115 times during which the relay 4 remains closed and the "up"-direction switch 1 is energized. The circuit for this coil extends from line conductor L1, through conductors 22, 61 and 76, the coil of relay 9, conductor 77, the other 120 set of contact members of the double-pole switch 12 on the car, conductor 78, contact members b of relay 4, conductors 69 and 79, contact members e of switch 1, and conductors 67, 66 and 28, to line conductor L2. The operation of relay 9, therefore, deenergizes relay 4 and opens the circuit excluding resistor R', and the car operates from the fourth to the fourteenth floor at speeds not greater 125 than high speed.

It frequently happens that, when a car is descending and arrives at the junction between the local and express zones, the attendant finds it necessary to re-enter the local 130

zone to serve the floors which may have been accidentally missed when the car was initially descending. Assuming that the attendant had moved the car out of the local zone to such an extent as to have caused actuation of inductor relay 11, the conditions of operation now existing would be such that the car would operate at express speed so that, upon re-entry of the car into the local zone, the car 10 would be travelling at such high speed as to make it extremely difficult to stop the car level with any of the floors in that zone.

It will be observed that the inductor irons or plates for actuating inductor relay 9 to 15 reduce the speed of the car from express speed to high speed must be placed somewhat in advance of the boundary between the express zone and the local zone, in order that sufficient time may be given to permit the 20 car to slow down from express speed to high speed and to be brought to rest at the first floor in the local zone, should service be desired at this floor. This advance distance may be several floors. For example, the inductor plate 15 for the car in hatchway A 25 will be approximately at the second floor level so that reduction in speed of the car will be initiated just after the car passes the second-floor level. This arrangement will 30 allow sufficient time for the car to reduce its speed from, say 900 feet per minute, to 600 feet per minute, before the car approaches that point in advance of the fourth floor at which relays 6 and 7 must be actuated to 35 bring the car to a stop at the fourth-floor level.

On the other hand, when the car is descending, it is necessary that inductor relay 40 11 shall operate just after the car passes the fourth-floor level, so that the car may then operate at express speed to the first floor. Hence, inductor plate 16, cooperating with inductor relay 11, must be mounted just below the fourth-floor level.

45 It frequently happens, however, that the attendant on a car discovers that a call for service in the local zone has been accidentally missed and that it is necessary to reverse the operation of the car to serve such call. If 50 the car has passed inductor plate 16 before such reversal occurs, it will be seen that the re-entry of the car into the local zone will be at such time as the car is operating under express-speed conditions, so that, even though 55 it is desired to give service at the floors within the local zone, the car is operating at such high speed that it cannot be stopped accurately at the floors, and particularly, it cannot be accurately stopped by the automatic landing devices, such as inductor relays 6 and 7.

For this reason, I have provided an additional inductor plate 15' mounted at a point approximately level with the fourth floor so that, if the car is reversed at any point between inductor plates 16 and 15, the re-entry

of the car into the local zone will cause inductor plate 15' to actuate inductor relay 9 to thereby reduce the speed of the car to high speed.

It has been found extremely desirable that 70 such arrangement be used particularly when the express speed is of a relatively high value. By this construction, it is insured that the car will operate at speeds not greater than high speed in the local zone under all conditions of operation. 75

The device more particularly embodying my invention thus provides an additional safeguard cooperating with one of a plurality of relays to ensure that proper speed shall 80 be maintained in a local zone if, for any reason, the operator has moved the car past the dividing line between the two zones, and the relay normally provided to ensure a change in the speed does not happen to operate. 85

The apparatus disclosed is merely illustrative, and I do not desire to be limited to the specific details shown, except as defined in the appended claims.

I claim as my invention:

90 1. In a control system for elevators, an elevator car operable in a hatchway past a plurality of floors, motive means for said car, means for controlling said motive means to cause said car to run at a plurality of different speeds, means defining a plurality of zones of operation for said car, each zone including a plurality of adjacent floors, said zone defining means including means operable by movement of said car in one direction within one predetermined distance of the boundary between two of said zones for actuating said control means to cause said car to travel at one of said speeds, means operable by movement of said car in said one direction within a lesser distance of said boundary for also actuating said control means to cause said car to travel at said one speed, and means operable by movement of said car in the opposite direction within a predetermined distance of the boundary between two of said zones for actuating said control means to cause said car to travel at one of said speeds, means operable by movement of said car in said one direction within a lesser distance of said boundary for also actuating said control means to cause said car to operate at another of said speeds. 95 100 105

110 2. In a control system for elevators, an elevator car operable in a hatchway past a plurality of floors, motive means for said car, means for controlling said motive means to cause said car to run at a plurality of different speeds, means defining a plurality of zones of operation for said car, each zone including a plurality of adjacent floors, said zone-defining means including means operable by movement of said car in one direction within one predetermined distance of the boundary between two of said zones for actuating said control means to cause said car to travel at one of said speeds, means operable by movement of said car in said one direction within a lesser distance of said boundary for also actuating said control means to cause said car to travel at said one speed, and means operable by movement of said car in the opposite direction within a predetermined distance of the boundary between two of said zones for actuating said control means to cause said car to travel at one of said speeds, means operable by movement of said car in said one direction within a lesser distance of said boundary for also actuating said control means to cause said car to operate at another of said speeds. 115

120 125 130 3. In a control system for elevators, an elevator car operable in a hatchway past a plurality of floors, motive means for said car, means for controlling said motive means to cause said car to run at a plurality of different speeds, means defining a plurality of zones of operation for said car, each zone including a plurality of adjacent floors, said zone-defining means including means operable by movement of said car in one direction within one predetermined distance of the boundary between two of said zones for actuating said control means to cause said car to travel at one of said speeds, means operable by movement of said car in said one direction within a lesser distance of said boundary for also actuating said control means to cause said car to travel at said one speed, and means operable by movement of said car in the opposite direction within a predetermined distance of the boundary between two of said zones for actuating said control means to cause said car to travel at one of said speeds, means operable by movement of said car in said one direction within a lesser distance of said boundary for also actuating said control means to cause said car to operate at another of said speeds.

- cause said car to run at said one speed, and means operable by movement of said car in the opposite direction within a predetermined distance of said boundary for actuating said control means to cause said car to operate at an increased speed.
3. In a control system for elevators, an elevator car operable in a hatchway past a plurality of floors, motive means for said car, means for controlling said motive means to cause said car to run at a plurality of different speeds, means defining a plurality of zones of operation for said car, each zone including a plurality of adjacent floors, said zone-defining means including a switch for actuating said control means to cause said car to operate at one of said speeds, and means for actuating said switch when said car traveling in one direction passes one point a predetermined distance in advance of the boundary between two of said zones and for also actuating said switch when said car passes another point a lesser distance in advance of the boundary of said zone, and a second switch operable by movement of said car in the other direction past a point adjacent to said boundary for actuating said control means to cause said car to operate at an increased speed.
4. In a control system for elevators, an elevator car operable in a hatchway past a plurality of floors, motive means for said car, means for controlling said motive means to cause said car to run at a plurality of different speeds, means defining a plurality of zones of operation for said car, each zone including a plurality of adjacent floors, said zone-defining means including means operable by movement of said car in one direction to a position adjacent to the boundary of two of said zones for actuating said control means to cause said car to operate at one of said speeds, means operable by movement of said car in the other direction to a position adjacent to said boundary for actuating said control means to cause said car to operate at the greater of said speeds and auxiliary means operable by movement of said car in said one direction to a point closer to said boundary than said first named point for actuating said control means to cause said car to operate at said lesser speed.
5. In a control system for elevators, the combination with an elevator operable over a predetermined path between a plurality of floors, a motor for said elevator operable at different speeds, means defining zones of operation along said path comprising magnetizable plates located adjacent the junction of said zones, and means, including relays on said elevator, to cooperate with said plates when the elevator approaches the boundary of a zone for controlling the motor to determine the speed thereof within said zone of an auxiliary magnetizable plate adjacent said junction to cooperate with one of said relays to ensure proper speed in the associated zone.
6. In a control system for elevators, the combination with an elevator operable over a predetermined path through a plurality of zones, a motor for said elevator selectively operable at a normally high speed and at an abnormally high speed through the respective zones, a plurality of magnetizable plates located adjacent the junction of said zones, and means, including a plurality of relays on said elevator, to cooperate with said plates when the elevator approaches the boundary of a zone for controlling the motor to change from one to the other of its speeds, of an auxiliary magnetizable plate also adjacent said junction to cooperate with one of said relays to control the motor to prevent operation at abnormally high speed in the zone associated with said relay.
7. In a control system for elevators, the combination with an elevator operable over a plurality of zones, a motor adapted to operate said elevator at different speeds in the respective zones, a plurality of magnetizable plates located adjacent the junction of two zones and means, including a plurality of electromagnetic relays on said elevator, to cooperate with said plates when the elevator approaches the junction of said zones for controlling the motor to change from one to the other of its speeds, of an auxiliary magnetizable plate also adjacent the junction of said zones to cooperate with one of said relays to cause the motor-controlling means to ensure a proper motor speed in the zone associated with said relay.
8. In a control system for elevators, the combination with an elevator operable over a plurality of zones, a motor adapted to operate said elevator at a normal high speed in one of said zones and at an abnormally high speed in the other of said zones, a plurality of magnetizable plates corresponding in number to the zones, one of said plates being located in a zone adjacent to the junction thereof, and means, including a plurality of electromagnetic relays on said elevator, for selectively cooperating with said plates for controlling the motor to change from one to another of its speeds when moving from one to another of said zones, of an auxiliary magnetizable plate located in one of said zones to cooperate with one of said relays to so control the motor as to ensure operation thereof at the normal high speed in the zone associated with that relay.
9. In the control system for elevators, the combination with an elevator operable at a normal high speed over a local zone and at an abnormal high speed over an express zone, an elevator motor adapted to operate at corresponding speeds, a magnetizable plate associated with each of said zones and located close to the junction thereof, and means, including

a pair of relays on said elevator, to cooperate selectively with said plates for controlling the motor to change from normal high speed in the local zone to abnormal high speed in the express zone and vice versa, of an auxiliary magnetizable plate spaced from the other plates to cooperate with one of said relays to control the motor to prevent operation thereof at abnormally high speed in the local zone.

10. In a control system for an elevator car operable over a predetermined path past a plurality of floors, a multi-speed motor for driving said car, means defining zones of operation along said path in each of which zones the speed of said car is limited to a predetermined speed different from the speed to which the car is limited in an adjacent zone, said means including a plurality of switches 15 each corresponding to a zone and operable to change the speed of said car prior to entry of the car into the corresponding zone, means for selectively operating said switches in accordance with the position of the car in the 20 said path, and means independent of said selectively operating means, for effecting the operation of a said switch to prevent the entry of the car into a zone corresponding to that switch at a speed in excess of the predetermined speed to which the car is limited in 25 that zone.

In testimony whereof, I have hereunto subscribed my name this 23rd day of May, 1929.

HAROLD W. WILLIAMS.
